UNITED STATES PATENT OFFICE

149,111

DESIGN FOR A CLOTHESPIN

Wayne H. Coble, Ann Arbor, Mich.

Application August 28, 1946, Serial No. 132,921

Term of patent 14 years

(Cl. D17—6)

To all whom it may concern:

Be it known that I, Wayne H. Coble, a citizen of the United States, residing at Ann Arbor, in the county of Washtenaw and State of Michigan, have invented a new, original, and ornamental Design for a Clothespin, of which the following is a specification, reference being had to the accompanying drawing, forming part thereof.

I claim:

The ornamental design for a clothespin, as shown.

WAYNE H. COBLE.
